(57) CLAIM

The ornamental design for a “golf bag with attached golf towel and bag,” as shown.

DESCRIPTION

FIG. 1 is a perspective view of a golf bag with attached golf towel and bag showing my new design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The broken lines showing of a human figure, golf clubs, a bottom surface and stitching are included for the purpose of illustrating environment and form no part of the claimed design.
